CLAIM

The ornamental design for an electronic atomizing device, as shown and described.

DESCRIPTION

FIG. 1 is a top, front, and left side perspective view of an electronic atomizing device according to an embodiment of my new design;

FIG. 2 is a bottom, rear, and left side perspective view of FIG. 1;

FIG. 3 is a front elevational view of FIG. 1;

FIG. 4 is a rear elevational view of FIG. 1;

FIG. 5 is a right side view of FIG. 1;

FIG. 6 is a left side view of FIG. 1;

FIG. 7 is a top plan view of FIG. 1;

FIG. 8 is a bottom plan view of FIG. 1;

FIG. 9 is a top, front, and left side perspective view of an electronic atomizing device according to another embodiment of my new design;

FIG. 10 is a bottom, rear, and left side perspective view of FIG. 9;

FIG. 11 is a front elevational view of FIG. 9;

FIG. 12 is a rear elevational view of FIG. 9;

FIG. 13 is a right side view of FIG. 9;

FIG. 14 is a left side view of FIG. 9;

FIG. 15 is a top plan view of FIG. 9; and,

FIG. 16 is a bottom plan view of FIG. 9.

The broken lines in the drawings depict portions of the electronic atomizing device that form no part of the claimed design.

The oblique shade lines show transparency.

1 Claim, 16 Drawing Sheets
